CLAIM

We claim the ornamental design for a display screen with graphical user interface, as shown and described.

DESCRIPTION

FIG. 1 is a front view of the first image of a display screen with graphical user interface showing our new design; and, FIG. 2 is a front view of a second embodiment thereof. The broken lines in the drawings, including the broken line text and display screen or portion thereof, are for illustrating environmental structure only and form no part of the claimed design.
